United States Patent

Des. 236,529
Patented Aug. 26, 1975

236,529

YARN HOLDER

Dolores M. Courtney, Alamo, Calif.
(P.O. Box 877, Danville, Calif. 94526)

Filed Mar. 18, 1974, Ser. No. 452,429

Term of patent 14 years

Int. Cl. D15—06

U.S. Cl. D47—5

FIG. 1

FIG. 3

FIG. 2

FIG. 4

FIG. 5

FIG. 6

FIG. 7

FIG. 1 is a perspective view of a yarn holder showing my new design;

FIG. 2 is a top plan view;

FIG. 3 is a side elevational view (both sides being the same);

FIG. 4 is a front elevational view;

FIG. 5 is a bottom plan view;

FIG. 6 is a rear elevational view;

FIG. 7 is a second embodiment of the design of FIG. 1.

I claim:

The ornamental design for a yarn holder, substantially as shown and described.
